UNITED STATES PATENT OFFICE.

ROBERT H. HOWARTH, OF ROTHSCHILD, WISCONSIN.

CORE FOR PAPER-ROLLS.

1,118,860.

Specification of Letters Patent.

Patented Nov. 24, 1914.

Application filed February 21, 1914. Serial No. 820,222.

To all whom it may concern:

Be it known that I, ROBERT H. HOWARTH, a citizen of the United States, residing at Rothschild, in the county of Marathon and State of Wisconsin, have invented certain new and useful Improvements in Cores for Paper-Rolls; and I do hereby declare the following to be a full, clear, and exact description of the invention, such as will enable others skilled in the art to which it appertains to make and use the same.

My invention relates to cores for use in paper rolls, especially in connection with those paper rolls which are used in the production of newspapers, or rolls of wrapping paper, or the like, where it is desired to positively drive the core from any suitable source of power while the material is being wound thereon.

It is my intention to provide a light, cheap and efficient core made of rolled paper, pasteboard, or the like, and which can be manufactured in any convenient lengths, and then cut into shorter lengths and fitted to suit the various axial lengths of the paper rolls for which such cores are intended; or a series of these cores may be used to form a composite core, all mounted on the same spindle.

My invention will be understood by reference to the accompanying drawings, in which the same parts are indicated by similar reference symbols throughout the several views.

Figure 1 is a side elevation showing several of the cores assembled on a single shaft for use in a paper mill, parts being broken away; Fig. 2 is a detail showing one of the cores removed from the spindle; Fig. 3 is a side elevation showing the core mounted on the spindle, the paper roll enclosing the core being omitted, and parts being broken away; Fig. 4 shows a section through the core and the centering collars, the spindle being shown in elevation, parts being broken away, and the section being along the line 4-4 of Fig. 3; Fig. 5 shows a section through the core along the line 5-5 of Fig. 4 looking in the direction of the arrows, the spindle and centering collar being omitted; and Fig. 6 is a detail view showing the metal reinforcing sleeve designed to be mounted in the end of the pasteboard roll.

A represents the shell of the core which is made of pasteboard, or other similar material, preferably spirally wound of six or

eight thicknesses of heavy paper, wound in reverse direction to break joints and insure stiffness, and cut in the desired length. This shell is cut away at each end, as at a, to receive the lug d of the centering collar D, which is secured on the spindle C in any convenient way, as by means of the set screw E. In the ends of the shell A the metal sleeve B is mounted, which sleeve is cut away at one end, as at b, and part of the cut-away portion is upwardly bent, as at b', to form a metal wear surface for the sides a' of the slot a, in the shell A. This sleeve slips over the reduced portion D' of the centering collar D and the curved flanges b' serve as wear plates to protect the edges a' of the slot a against wear from the lug d projecting axially from the shoulder d' of the collar D, as shown most clearly in Fig. 3.

The spirally-wound pasteboard tube may be made as long as desired, and then may be cut up into the desired lengths, and the ends of each section may be then cut away, as at a, and suitable sleeves B inserted; and these sections so constructed may be slid over the end of the spindle C and secured and centered on same by means of the collars D with the lugs d.

It will be obvious that various modifications might be made in the herein described apparatus, and in the construction, combination and arrangement of parts which could be used without departing from the spirit of my invention.

Having thus described my invention what I claim and desire to secure by Letters Patent of the United States is:

1. The combination with a core comprising a hollow shell composed of a series of strips of heavy paper spirally wound in reverse direction and axially indented at each end, with a reinforcing metal sleeve snugly fitting in the end of said core and axially indented to register with the indentations in said paper core, and having curved flanges engaging the sides of said axial indentations in said core and holding said sleeve in place, and protecting said core from wear, of a spindle passing through said hollow shell, and collars secured on said spindle, and having lugs projecting into said indentations in said core, and said sleeve, substantially as described.

2. The combination with a core comprising a hollow shell composed of a series of strips of heavy paper spirally wound in re-

verse direction and axially indented at each end, with a reinforcing metal sleeve snugly fitting in the end of said core and axially indented to register with the indentations in said paper core, and having curved flanges stamped out of said indented portion, said curved flanges engaging the sides of said indentations in said core and holding said sleeve in place, and protecting said core from wear, of a spindle passing through said hollow shell, and collars secured on said spindle, and having reduced portions projecting into said metal sleeves, and having lugs above said reduced portion projecting into said indentations in said core, and said sleeve, substantially as described.

3. A core for use with metal spindles provided with radially-projecting lugs, comprising a hollow shell composed of a series of strips of heavy paper spirally wound in

reverse direction and indented at each end with a reinforcing metal sleeve snugly fitting in the end of said core and indented to register with the indentations in said paper core, and having curved flanges engaging the sides of said indentations in said core and holding said sleeve in place, and protecting said core from wear, the said metal sleeve being adapted to slip over said spindle, and the said curved flanges being adapted to engage the lugs on said spindle, substantially as and for the purposes described. 25 30

In testimony whereof, I affix my signature, in presence of two witnesses.

ROBERT H. HOWARTH.
